[57] CLAIM

The ornamental design for a combined reversible sprinkler nozzle and support ring, as shown and described.

DESCRIPTION

FIG. 1 is a bottom perspective of a combined reversible sprinkler nozzle and support ring showing my new design;

FIG. 2 is a top plan view thereof;

FIG. 3 is a bottom perspective view of a second embodiment thereof;

FIG. 4 is a top plan view of FIG. 3;

FIG. 5 is a bottom perspective view of a third embodiment thereof;

FIG. 6 is a bottom perspective view of a fourth embodiment thereof;

FIG. 7 is a bottom perspective view of a fifth embodiment thereof;

FIG. 8 is a bottom perspective view of a sixth embodiment thereof;

FIG. 9 is a bottom perspective view of a seventh embodiment thereof;

FIG. 10 is a bottom perspective view of an eighth embodiment thereof;

FIG. 11 is a bottom perspective view of a ninth embodiment thereof;
FIG. 12 is a bottom perspective view of a tenth embodiment thereof;

FIG. 13 is a bottom perspective view of an eleventh embodiment thereof; and
FIG. 14 is a bottom perspective view of a twelfth embodiment thereof.
